MEANS FOR THE SANITARY DISPOSITION
OF FECAL AND OTHER REFUSE MATERIALS

George Owens Harm, Warren, Ohio

Application July 28, 1938, Serial No. 221,780

25 Claims. (Cl. 4—124)

This invention relates generally to a means for the sanitary handling and disposition of malodorous material capable of initiating and/or spreading infection.

The embodiment of my invention as disclosed herein is in the form of a dry toilet, in the operation of which fecal matter is initially received upon a moisture proof conveyor; the conveyor is then formed into a sealed tube; and this tube and its contents are conveyed to a suitable collection point. While no water is employed in the operation of removing the fecal matter from the bowl or trough-like support of the toilet, nevertheless, because of the analogy between the operation of the apparatus herein in removing such fecal matter and the use of water in the ordinary toilet for effecting the same result, I have designated the mechanism employed herein for such removal as "flushing mechanism."

The forming of the conveyor into a sealed tube prevents the escape of offensive odors into the atmosphere adjacent to and surrounding the toilet and enables the fecal matter to be retained in such isolated condition until finally disposed of and rendered non-infectious, as by drying and/or burning, or by subjecting the same to treatment by suitable chemical reagents.

The toilet herein comprises generally three parts. The first part consists of a bowl in passing above the bottom of which a conveyor of moisture-proof paper or similar moisture-repellent material is formed into an open-top pocket for the reception of feces and is intermittently advanced by the operation of the second part, which comprises what I have termed a combined flushing and tube-forming mechanism. The third part comprises a receptacle into which successive tubular portions or compartments of the conveyor and their contents are delivered and from which they may be removed when necessary or desirable.

In the drawings forming a part hereof, wherein the preferred embodiments of my invention are illustrated, Fig. 1 represents a perspective view of the cabinet in which the operative parts of the toilet are located, the covers for the cabinet being closed; Fig. 2 a similar view, with the cover elevated; Fig. 3 a central longitudinal section, on an enlarged scale, taken through the apparatus shown in Figs. 1 and 2; Fig. 4 a diagrammatic view in perspective showing the form which is given to the conveyor sheet as it is drawn from its roller across the bowl and is carried through the flushing and tube-forming mechanism; Fig. 5 is a plan view of the bowl and combined tube-forming

and flushing mechanism; Fig. 6 is a sectional detail corresponding to the line 6—6 of Fig. 5, the conveyor being omitted; Fig. 7 a detail in section taken on the line 7—7 of Fig. 6 and showing the connections between the rack member of the flushing mechanism and the pinion which operate the gripper jaw spindles; Fig. 8 a detail in perspective of the discharge spout of the flushing mechanism which also assists in shaping the paper conveyor passing therethrough; Fig. 9 a detail in perspective of the frame which supports the flushing mechanism, showing the manner in which the reciprocating framework of the latter is supported thereby; Fig. 10 a side elevation, on a reduced scale, of said frame; Fig. 11 a detail in elevation of the front or receiving end of the receptacle into which the tube and its contents are delivered; and Fig. 12 an end elevation of a modification of the spout and sealing mechanism shown in the preceding views.

Describing the parts by reference characters, and with particular reference to the embodiment of my invention shown in Figs. 1—11, A represents the front wall of a cabinet in which the operative parts of my toilet are located, the said cabinet also including a removable end wall A', a rear wall A², a bottom wall A³ and a cover A⁴. From the end of the cabinet opposite the wall A', there is an extension comprising a front wall B, an end wall B', a rear wall B² and a cover B³. The bottom of the extension is preferably open except for angle rails B⁴, on which the bottom of the receptacle C rests, said rails being supported by flanges B⁵ at the bottom of the front and rear walls and the said receptacle being vertically removable from the cabinet extension. The receptacle C is provided with a cover C' and with a slot C² in the front end wall C⁴ which is located in proximity to the rear end of the cabinet A—A⁴. This slot is formed between rearwardly convergent flanges C⁵ to each of which is secured a yieldable gate C⁶, preferably of rubber, which gates will engage opposite sides of the spout and of the tubular conveyor, irrespective of variations that may occur in the distension of the latter.

In an opening A⁵ in the front wall A of the cabinet there is pivotally mounted a holder in which a roll of toilet paper may be supported, this holder comprising angularly disposed plates D and D' arranged at right angles to each other, and hinged adjacent to their junction to the front wall A, as shown at D², with side straps D³ connecting the said plates and constituting a support for the core of a roll E of toilet paper. The plates D and D' are so constructed and arranged

that either the one or the other will close the opening A⁵, whether the holder is in open or closed position.

- 5 F denotes a cover, additional to the cabinet cover A⁴, which overlies the flushing mechanism and which also overlies the marginal portion of the bowl. The cover F is shown as supported by upper corner brackets G carried by the main section of the cabinet. Adjacent to one end, it is 10 provided with an opening F', preferably of generally triangular outline, which is adapted to register with the opening in the seat thereabove, the said opening F' being surrounded by a downwardly projecting flange, the front wall F² of 15 which is shown as substantially parallel with the front wall A' of the cabinet and the walls F³ of which converge rearwardly.

The bowl shown herein comprises a downwardly and rearwardly inclined bottom 10, generally triangular in form, with its widened end at the front, and rearwardly convergent side walls 11 extending upwardly from each side of the bottom, the bowl being supported at its front end from hangers 12 having their upper ends flanged 20 and secured to and beneath the overhanging flanges of the side walls A and A². The rear ends of the side walls of the bowl are preferably secured to the cross member C', as by ears 11a.

13 denotes a roll of moisture-proof paper, the core 14 of said roll being supported in slots 12a in the hangers 12. This paper constitutes a conveyor for fecal matter deposited thereon above the bottom of the bowl. 15 denotes a roller located above and in front of the front end of the 25 bowl over which the paper conveyor passes.

The flushing and tube-forming mechanism comprises a plurality of reciprocal parts which are carried by a frame supported in the rear portion of the cabinet section A—A⁴. The frame 30 which supports said mechanism comprises a front transverse angle member 16 which is fastened to the cross member C', as by screws 17, a rear transverse angle member 18 which is supported by ears C¹³ extending from the transverse member C¹² at the rear of the main cabinet section. The transverse members 16 and 18 are also connected by marginal side members 19 and 20. Ears 16^a and 18^a depending from the ends of the 35 downwardly extending flanges of the angle members 16 and 18 are provided with openings for the reception of guide rods 21 and 22 which are arranged equidistantly from and parallel with the longitudinal center of the frame. The marginal side member 19 is also provided with hangers 23 which support a ratchet bar 24 having wide and deep notches 25 at opposite ends thereof and narrower intermediate notches 26. The frame 40 thus described supports the movable parts of the flushing and tube-forming mechanism to which 45 reference has been made hereinbefore.

Projecting from the rear member 18 of the framework are bracket members 27, 27^a and 28. Slidably mounted in the bracket members 27 is a plunger 29 having at one end a cross pin 30, 50 the opposite end of said plunger cooperating with a pad 31 carried by the bracket member 28, for a purpose to be described hereinafter.

32 denotes a spring surrounding the plunger 29 and bearing at one end against the bracket member 27 and at its opposite end against a pin 33 carried by the plunger, whereby the spring tends to move the end of the plunger mounted in the bracket 27^a into engagement with the pad 31. The end of the plunger 29 which projects through 55 the bracket member 27 rides within a slot 35

provided in a cam block 34, the cross pin being adapted to ride along the cam surfaces 34^a of said block. This cam block is mounted on the rear end of the rod 36, the opposite end of the rod being slidably mounted in a part of the frame structure of the flushing and tube-forming mechanism, which will now be described.

Flushing and tube-forming mechanism

The flushing and tube-forming mechanism 10 comprises generally a supporting framework slidably mounted on the rods 21 and 22; a pair of vertical spindles supported by said framework; sealing rollers mounted on the upper portions of said spindles; tube-gripping members mounted on the lower portions of said spindles; pinions on the upper ends of said spindles; a double rack carried by the first mentioned frame on the centerline thereof and engaging said pinions and operating to rotate the latter as the flushing and tube-forming mechanism is moved to and fro along said frame; a one-way driving connection between each pinion and its spindle; a discharge spout carried by and extending rearwardly from the framework of said mechanism; guide members secured to the front end of the framework for the purpose of assisting in shaping the paper conveyor into tubular form; and means for reciprocating the said mechanism.

The framework for the flushing and tube-forming mechanism is indicated generally at H, and is preferably a casting having a bottom 37, approximately rectangular in outline, vertical front corner posts 38, vertical rear corner posts 39, and upper side members 40 connecting the opposed front and rear corner posts. The front corner posts are provided each with a forwardly extending projection 38^a, the inner faces 38^b of the said projections being rearwardly convergent, for a purpose to be described. To the rear corner posts, there is bolted or otherwise suitably secured, a spout 41 which is preferably elliptical in section, said spout being provided with a longitudinal slot 42 in the top thereof located in a vertical plane extending through the longitudinal center of the frame 16—18 and through the longitudinal center of the framework H. The spout is also provided at its front end with lugs 43 by which it may be bolted to the rear corner posts. The inner edges of the rear corner posts are preferably rounded to enable each to form in effect a continuation of the front of the adjacent rounded inner wall of the spout. The side members 40 of the framework H are provided with projecting ears 40^a having apertures therethrough whereby the framework is slidably mounted upon the rods 21 and 22. The front end of the rod 36 is slidably mounted in a flange 44 carried by one of the rear corner posts 39.

45 denotes a pair of vertical spindles arranged equidistantly from the center line of the framework H and each having its lower end rotatably supported in a ball bearing 46 carried by the bottom member 37 of the said framework and its upper end rotatably mounted in a ball bearing 47 carried by a cover plate 48 which is secured to the tops of the corner posts, as by screws 49. Each of these spindles is shown as provided with an upper disk 50 and a lower disk 51, rigid therewith, the said disks being located below the tops of the spindles and the disks on each spindle being provided with two sets of vertically aligned openings, one set 52 being located closely adjacent to the spindle and the other set 53 being located adjacent to the peripheral portions of 55

said disks. In the former pairs of aligned openings there are mounted pins 54 each surrounded by a spring 55 which normally project the upper ends of the pins above the tops of the disks 50. The pins 56 are mounted in the other pairs of vertically aligned openings 53, each being surrounded by a spring 57 which normally projects the upper ends of the pins above the tops of the disks 50.

5 58 denotes arms mounted respectively in slots 59 formed in the upper ends of the side members 40 of the framework H. Each of these arms is provided with a cam 58^a on the under surface thereof, and the inner ends of these arms are so located as to enable the cams to ride over and depress the pins 56 when the spindles are operated in the manner to be described hereinafter. Mounted on each spindle 45, between the upper disk 50 and the ball bearing 47 thereon, is the hub 61 of a pinion 60, each of said hubs being loosely mounted on their respective spindles. Each pinion is provided on its under surface with a cam 62 which is adapted to ride over the top of the pin 54 therebeneath when the said pinion 10 is rotated in one direction by its engagement with the teeth on one side of a double rack 63 which is supported above the center line of the framework H by the front and rear members 16 and 18 of the frame on which the flushing mechanism is mounted.

15 30 35 40 45 50 55 60 65 70 75

The spindles 45 each support a tube-gripping member, the said members being adapted to engage the opposite sides of the front end of the tube formed within the spout 41 and to substantially close the front end of the tube and to carry the tube and the contents thereof into the receptacle C by the delivery movement of the flushing mechanism, which movement also serves to draw another increment of the conveyor paper 40 from the roll 13 across the bowl to replace that removed by said delivering movement. Each of the gripping members is preferably in the form of a vertical metallic blade 64 having the central portion thereof recessed to provide a seat 45 for a pad 65, adapted to frictionally engage one side of the paper tube. The material which I have found suitable for such pads is sponge rubber. The gripping members are slidably mounted in their respective spindles by pins 66, springs 67 surrounding the said pins and, when the gripping members are in operative relation to the paper tube, yieldingly pressing the said gripping members toward each other and in engagement with the said tube. It will be noted that the bottoms of the gripping members are spaced a short distance above the bottom 37 of the framework H. The purpose of this spacing will be explained hereinafter in connection with a description of the complete operation of the apparatus.

60 65 70 75 80 85 90 95

When the parts of the flushing mechanism are in the operative positions shown in Figs. 5 and 6, the paper of which the conveyor is formed will extend upwardly between the gripping members and between rollers having their upper ends surrounding the disks 50 and their lower ends supported by annular flanges 51^a on the bottoms of the disks 51. Each of these rollers comprises a cylindrical base 68, preferably of metal, said base supporting a cylindrical covering 69 of yieldable friction material, preferably sponge rubber.

Pivoted to the outer side of one of the side members 40 of the framework H is a pawl 70, the 75 said pawl being provided with a weight-arm 71

which tends to swing the nose of the pawl downwardly.

Pivotedly mounted on the front posts 38 of the said framework and constituting in effect rearwardly convergent extensions of the rearwardly convergent front surfaces 38^a of said posts, are inverted U-shaped guides J, preferably of sheet metal, which receive the upper edges of the opposite sides of the paper conveyor extending rearwardly across the bowl and cooperate in 10 ensuring the delivery of the conveyor to the flushing and tube forming mechanism in a shape which will enable the latter readily to complete the formation of the conveyor into a tube.

15 20 25 30 35 40 45 50 55 60 65 70 75

72 denotes a seat which is pivoted to be swung backwardly against the cover A⁴, when the latter is in the position shown in Fig. 2, and to be swung downwardly in operative relation to the flanged opening provided in the front end of the cover F. 73 denotes a stud secured to the cover 20 plate 48 and extending through a longitudinally-extending slot 74 provided in the cover F, said stud having an operating handle 75 on its upper end.

25 30 35 40 45 50 55 60 65 70 75 80 85 90 95

With the parts constructed and arranged as described, the operation will be as follows: When it is desired to flush the bowl, the operator grasps the handle 75 preliminarily to moving the flushing and tube-forming mechanism rearwardly. At this time, the gripping members 65, 65 30 are in engagement with opposite sides of the conveyor paper 13 and hold them in engagement with each other. As the handle is moved rearwardly the gripping members not only hold the opposite sides of the conveyor paper together 35 but pull the conveyor paper from the roll 13 and across the bowl. During this movement, the pinions 60 are revolved by engagement with the teeth on the rack 63 but turn idly on the tops of their respective spindles, it being noted that the number and spacing of the teeth on the pinions and rack are such that the pinions are each given a complete revolution by a full stroke of the framework H and spout 41. The cams 62, during the revolutions of the pinions imparted thereto by this rearward or delivery stroke, travel away from the pins 54 and, at the end of the stroke, will have made a complete revolution, and the pins will have ridden under the cams 62 and have assumed the positions shown in 50 Fig. 7. As the cams ride over the pins 54, any tendency to rotate the spindles, due to the frictional drag between the cams and the tops of the pins 54 and the pull of the paper, will be prevented by the engagement of the shoulders of the cam bars 58 with the pins 56. As the spindles are not rotated during this movement, the rolls 68, 69 do not rotate, but travel, without turning, at the same rate of speed as the upper edges of the paper conveyor tube therebetween. 55 This operation causes the spout to enter the receptacle C. Also, at the end of this stroke, the base 34^b of the cam block 34 is engaged by the flange 44 on the adjacent rear post 39 of the framework H, thereby moving the cam block 65 rearwardly, whereupon the cross pin 30 slides down the cam surfaces 34^a and the spring 32 projects the plunger 29 toward the pad 31, the plunger and pad serving to grip the top edges of the conveyor tube therebetween and in line 70 with the slot in the top of the spout 41, thereby to retain the tube against longitudinal movement during the return stroke of the flushing mechanism.

75 During the return stroke of the flushing mech-

anism, the upper edge of the conveyor tube is held between the plunger and the pad, retaining in the receptacle C the portion of the conveyor tube and the contents thereof that were formerly in said spout. During this same stroke, the pinions 60 are each rotated by the rack 63 in the reverse direction from that which was imparted thereto by the delivery or flushing stroke. At the start of this return stroke, the backs of the cams 62 engage the pins 54 and rotate the spindles, which results in rotating the rollers 68, 69 in sealing engagement with the upper edges of the tube in front of the spout 41 and in sealing such edges, it being noted that the conveyor paper 13 is not only moisture-proof but is preferably coated with latex, or similar adhesive material, along its upper edges, which material will enable these edges to adhere to each other under pressure but will not adhere to surfaces which are not similarly coated. In fact, I have found it practicable to employ a coating of latex for the entire refuse-receiving surface of the conveyor paper which is wound upon the roll, the latex serving not only to make the paper moisture-proof, but also enabling the upper edges to be sealed together into tubular form by the action of the rollers 68, 69 and the conveyor tube to be formed into compartments by the engagement of the gripping members with opposite sides thereof. The rollers 68, 69, being of greater diameter than the diameter of the respective pinions thereabove, would exert a pull upon the paper during the return stroke of the flushing mechanism. This is avoided by mounting the rollers in the manner shown herein, whereby they are capable of slipping upon their respective disks 50 and 51. The rotation imparted to the spindles by the return stroke of the flushing and tube-forming mechanism also moves the gripping members 65, 65 away from the conveyor tube. At the end of the return stroke, the cams 62 are still back of their pins 54, in position to be moved away from them at the next flushing operation, and the gripping members have been brought around to the positions shown in Fig. 6; the pins 56 also will have passed under the cams 58 and will have assumed the positions shown in Fig. 7. As the flushing and tube forming mechanism nears the end of its return stroke, the flange 44 engages the head of the rod 36, moving the cam block 34 forwardly until, at the end of said stroke, the parts will be in the position shown in Fig. 9, with the end of the plunger 29 and the pad 31 out of gripping engagement with the top edges of the conveyor tube.

Due to the pawl-and-ratchet shown and described herein, the operator is compelled, once he starts to move the flushing mechanism in either direction, to complete the full stroke thereof. This is due to the engagement of the nose of the pawl with the intermediate recesses 26 during such strokes, the pawl being incapable of reversal until the flushing mechanism shall have made a complete stroke in either direction, at the ends of which strokes the pawl will be in one or the other of the wide and deep slots 25 in the ends of the ratchet bar 24, which will enable the pawl to be reversed and permit the flushing mechanism to be moved in the opposite direction.

Reference has been made heretofore to the fact that the bottoms of the gripping members 65, 65 are spaced above the bottom of the plate 37 of the frame H. This is for the purpose of

allowing a channel for urine or other liquid to be formed in the bottom of the portion of the tubular pocket within the spout.

With the parts made in substantial accordance with the relative dimensions shown herein, two reciprocations of the flushing mechanism will be required to effect the complete removal and renewal of the pocket receiving portion of the conveyor.

With an apparatus constructed and operated in the manner shown and described herein, and with the use of a suitable adhesive for the waterproofing material applied to the conveyor paper, each operation of the flushing mechanism will result in forming into a tubular pocket a portion of the conveyor paper which has previously extended across and been supported by the bottom of the bowl, or trough-like support, together with the material deposited thereon; in sealing the top of such tubular pocket; and in substantially closing off the front or receiving end of said tubular pocket from the bowl and the seat. Where the upper surface of the paper is completely coated with such adhesive material, successive operations will deliver into the receptacle C a continuous tubular container consisting of practically isolated compartments, each compartment containing the feces, etc., delivered thereto from a preceding flushing operation. The receptacle C, with its contents may be removed and the contents disposed of in any sanitary manner.

In Fig. 12, there is shown a construction of spout which serves to effect a temporary seal between the top edges of the conveyor paper, without the necessity for applying adhesive to the upper edges nor, in fact, without the necessity for using for the conveyor any paper other than moisture-proof paper of sufficient strength for the purposes desired. In this view, 76 denotes a spout which is of the same general form as the spout 41 and which is provided at its front with lugs 77 by which it may be bolted to the rear posts of the framework H in the same manner as is the case with the spout 41. A centrally arranged slot through which the upper edges of the conveyor paper 13c extends is provided by a longitudinal channel 78 formed within a rib 79 on the top of one of the sides of the spout and the adjacent inwardly projected edge 80 of the top of the other side. The parts 78, 79 and 80 serve to form a U-shaped bend in, and a temporary seal or closure for, the tubular conveyor paper. In view of the fact that the tubular seal is effected by the spout itself, the sealing rollers may be dispensed with.

From the foregoing description and illustration, it will be evident that I have produced a portable dry toilet which is capable of handling and disposing of feces conveniently and in a completely sanitary manner and which is capable of use wherever lack of sewage facilities may occur.

While I have necessarily described my invention in detail in connection with the specific embodiment illustrated in the drawings hereof, I do not thereby intend to limit its use to the details of construction shown and described herein except as such details may be embodied in the claims hereof.

Having thus described my invention, what I claim is:

1. Mechanism for the sanitary handling and disposition of malodorous refuse comprising, in combination, means for supporting and positioning successive portions of an elongated strip of conveying and wrapping material in a form to

constitute successive refuse-receiving pockets, said means being located externally of the said pockets, means for moving successive portions of the said material through the pocket-forming means, means located beyond the pocket-forming means for shaping the material into a continuous tubular package as it is so moved, and means for uniting the edges of said package.

2. Mechanism for the sanitary handling and disposition of malodorous refuse comprising, in combination, means for supporting and positioning successive portions of an elongated strip of substantially moisture-proof conveying and wrapping material in a form to constitute successive refuse-receiving pockets, said means being located externally of said pockets, means for moving the said material intermittently through the pocket-forming means, and means located beyond the pocket-forming means for shaping the material into a continuous tubular package from and for uniting the edges of the material after it has been so shaped.

3. Mechanism for the sanitary handling and disposition of malodorous refuse comprising, in combination, means for supporting successive portions of a continuous conveyor of wrapping material in an extended position for the reception of refuse thereon, said means being located externally of the portions thus supported, means for moving said conveyor thereby to advance said receiving portions, means including a reciprocable spout for forming the portions thus advanced into a continuous tube, and a receptacle into which the tube is delivered by said spout, said receptacle having a wall provided with a slot, and yieldable gates on opposite sides of said slot through which the tube is delivered by said spout.

4. A dry toilet for the sanitary handling and disposition of fecal matter comprising, in combination, a closet seat having an opening, means for rotatably supporting a roll of substantially moisture-proof conveying material, means for shaping successive portions of the said conveying material into the form of open-top pockets located below the opening of said seat and having upturned rearwardly convergent sides, means for engaging the sides of successive pockets thereby to pull successive portions of the said moisture-proof material from the said roll and beneath the opening in said seat through the pocket-forming means, and means for sealing the upper edges of the material delivered from said pocket-forming means.

5. A dry toilet for the sanitary handling and disposition of fecal matter comprising, in combination, a closet seat having an opening, a trough-like support having a bottom, of means for supporting a roll of moisture-proof conveying and wrapping material adjacent to the front end of said trough-like support, means for shaping successive portions of the moisture-proof material above the said support into the form of pockets each having upturned rearwardly convergent sides, means located rearwardly of the trough and of the pocket-forming means for engaging the sides of successive pockets thereby to pull successive portions of the said moisture-proof material from the said roll across and above the bottom of the trough and through the pocket-forming means, and means for sealing the upper edges of the material delivered from the said pocket-forming means.

6. Mechanism for the sanitary handling and disposition of malodorous refuse comprising, in combination, means for supporting a roll of sub-

stantially moisture-proof conveying material, means for shaping successive portions of the said material into the form of refuse-receiving pockets each having upturned rearwardly convergent sides, means for engaging the sides of the rear portions of successive pockets thereby to pull successive portions of the said conveying material from the said roll and through the pocket-forming means, means for forming into a continuous tube the material delivered from the pocket-forming means, and means for closing the edges of the material which has been formed into said continuous tube.

7. Mechanism for the sanitary handling and disposition of malodorous refuse comprising, in combination, a trough like support having a bottom, of means for supporting a roll of paper material adjacent to the front of the bottom of said support, a cover for said support having an opening defined by downwardly directed and rearwardly convergent side flanges extending within said support, a reciprocable flushing device located rearwardly of the said support and having rearwardly convergent guiding means engaging the upper edges of the rear portion of the said paper material which extends across the bottom of the said support, thereby to form the portion of the material above the support into an open-top pocket the rear portions of the sides whereof are located outside the said flanges, means carried by the said flushing device for shaping the portion of the material delivered thereto into a continuous tube and for pulling the said material from the roll and across and above the bottom of the said support by the movement of the said device away from the said support and means also carried by said flushing device for sealing the upper edges of the said tube.

8. Mechanism for the sanitary handling and disposition of malodorous refuse comprising, in combination, means for supporting a conveyor of substantially moisture-proof material, a reciprocable flushing and tube-forming device at the rear of the means for supporting said conveyor and having rearwardly convergent guiding means engaging the upper edges of the sides of the portion of the said material in front of said device thereby to assist in forming said portion into an open-top pocket, the said device including a spout having a slot extending the length thereof and receiving the material delivered to the said device through the said guiding means with the top edges of the material projecting above said slot, means carried by the said device for engaging the material delivered thereto, thereby to enable the material to be moved rearwardly by the rearward movement of the said device, means for engaging the material projecting through the rear end of the spout at substantially the end of the rearward movement of the said device, and means operative by the movement of the said device in the opposite direction for sealing the upper edges of the material.

9. Mechanism for the sanitary handling and disposition of malodorous refuse comprising, in combination, means for supporting successive portions of a refuse-removing conveyor in a form to constitute successive open-top refuse-receiving pockets, a reciprocable flushing device, a tube-forming member carried by said device and projecting rearwardly therefrom, gripping members carried by said device in front of said tube-forming member for engaging and pressing together opposite sides of the rear portions of the successive pockets formed in front of said device,

- means operative at substantially the end of each rearward or flushing movement of said device for releasing the gripping members from engagement with the sides of the rear portion of the pocket in front of said device and for holding the conveyor against longitudinal movement, and means operative at substantially the end of each forward or return movement of the said device for again bringing the gripping members into engagement with the sides of the rear portion of the pocket then adjacent to the said device and for releasing the said holding means.
10. Mechanism for the sanitary handling and disposition of malodorous refuse comprising, in combination, a trough like support having a bottom, of means for supporting a roll of refuse removing material adjacent to the front of the said bottom, a cover for said support having an opening defined by downwardly directed and rearwardly convergent side flanges above the bottom of said support, a reciprocable flushing and tube-forming device located rearwardly of the said support and having guiding means engaging the upper edges of the sides of the rear portion of the said material which extends across the bottom of the said support, thereby to form the portion of the material above the support into an open-top pocket the rear portions of the sides whereof are located outside the said flanges; the said device including a spout having a slot extending the length thereof and receiving the material delivered to the said device from the support with the top edges of the material projecting above said slot, means carried by the front portion of the said device for engaging the material delivered thereto, thereby to enable the material to be drawn from the roll and across the bottom of the support by the movement of the said device away from the support, means for engaging the material adjacent to the rear of the spout at substantially the end of the delivery or flushing movement of the said device; and means operative by the movement of the said device in the opposite direction for sealing the upper edges of the material.
11. Mechanism for the sanitary handling and disposition of malodorous refuse comprising, in combination, means for supporting a substantially moisture-proof refuse-removing conveyor, a reciprocable flushing and tube-forming device at the rear of the conveyor supporting means, means in front of said device for forming the portion of the conveyor in front of said device into an open top pocket, said device including a tube-forming spout projecting rearwardly therefrom and having a slot in the top of and extending the length thereof, said spout receiving the portion of the conveyor delivered to the said device through the said forming means, with the top edges of the said conveyor portion projecting into said slot, gripping members carried by the said device in front of the said spout for engaging opposite sides of the front of the conveyor portion delivered to said spout, means operative at the end of the rearward movement of the said device for releasing the gripping members from engagement with the front of said conveyor portion, means operative at the end of the forward movement of the said device for bringing the gripping members again into engagement with the opposite sides of the said conveyor, and means operative by the forward movement of the said device for uniting the top edges of the portion of the conveyor which is within said slot.

12. Mechanism for the sanitary handling and disposition of malodorous refuse comprising, in combination, means for supporting a moisture-proof conveyor, a reciprocable flushing and tube-forming device of the conveyor supporting means, means in front of said device for forming the portion of the conveyor in front of said device into an open-top pocket, said device including a rearwardly projecting spout having a slot in the top of and extending the length thereof, said spout receiving the portion of the conveyor delivered to the said device through the said forming means with the top edges of the said conveyor portion projecting above said slot, gripping members carried by the said device in front of the said spout for engaging opposite sides of the front of the conveyor portion delivered to said spout, means operative at the end of the rearward or flushing movement of said device for engaging the portions of the conveyor adjacent to the rear end of the spout and for releasing the gripping members from engagement with the front of said conveyor portion, means operative by the forward or return movement of the said device for sealing the upper edges of the conveyor, and means operative at the end of the return movement of the said device for bringing the gripping members again into engagement with the opposite sides of the said conveyor and for releasing the means brought into engagement with the conveyor portion adjacent to the rear end of the spout at the end of the flushing movement of said device.

13. Mechanism for the sanitary handling and disposition of malodorous refuse comprising, in combination, means for supporting a conveyor, a reciprocable flushing and tube-forming device at the rear of the conveyor supporting means, rearwardly convergent guiding means engaging the sides of a portion of the said conveyor in front of said device thereby to form said portion into an open-top pocket, the said device including a rearwardly projecting spout having a slot in the top of and extending the length thereof, said spout receiving the portion of the conveyor delivered to the said device through the said guiding means with the top edges of the said conveyor portion projecting above said slot, a frame reciprocably supporting the said flushing and forming device, gripping members carried by the said device in front of the said spout for engaging opposite sides of the front of the conveyor portion delivered to said spout, means carried by said frame for engaging the said conveyor portion at the end of the flushing movement of the said device, means carried by said device and operative at substantially the end of the rearward or flushing movement thereof for disengaging the gripping members from the front of said conveyor portion, sealing members carried by said device and operative to move along and press together the upper edges of the conveyor during the forward or return movement of the said device, thereby to seal the said edges, and means operative at substantially the end of the return stroke of the said device for moving the said gripping members into engagement with opposite sides of said conveyor and for releasing the engaging means carried by the frame.

14. Mechanism for the sanitary handling and disposition of malodorous refuse comprising, in combination, means for supporting a conveyor of moisture resistant material, a reciprocable flushing and tube-forming device located at the rear of the conveyor supporting means and hav-

ing rearwardly converging guiding means engaging the upper edges of the sides of a portion of the said conveyor in front of said device thereby to form said portion into an open-top refuse receiving pocket, the said device including a rearwardly projecting spout having a slot in the top of and extending the length thereof and receiving the portion of the conveyor delivered to the spout through the said guiding means, with the top edges of the said conveyor portion projecting above said slot, a frame reciprocably supporting the said flushing and tube-forming device, gripping members carried by the said device in front of the said spout for engaging opposite sides of the front of the conveyor portion delivered to said spout, means carried by said frame for engaging the rear of said conveyor portion at the end of the rearward movement of the said device, means carried by said device and operative at substantially the end of the rearward movement thereof for disengaging the gripping members from the front of said conveyor portion, sealing rollers carried by said device and operative to roll along and press together the upper edges of the conveyor during the forward movement of the said device, thereby to seal the said edges, and means operative at substantially the end of the forward stroke of the said device for moving the said gripping members into engagement with opposite sides of said conveyor and for releasing the engaging means carried by the frame.

15. Mechanism for the sanitary handling and disposition of malodorous refuse comprising, in combination, means for supporting successive portions of a moisture resistant refuse removing conveyor in an extended position for the reception of refuse thereon, a reciprocable combined flushing and tube-forming device through which successive receiving portions of the said conveyor are moved and shaped into tubular form, the said device comprising a spout having an open slot extending longitudinally through the top thereof, vertically arranged spindles supported by said device on opposite sides of the front or receiving end of said spout, a vertically extending gripping member carried by each spindle, a pinion mounted loosely on the upper end of each spindle and above the top of said spout, a frame along which the said flushing and tube-forming device is reciprocable, a double rack supported by said frame and engaging the said pinions, sealing rollers also loosely supported by the upper portions of said spindles below the pinions thereof and above the gripping members, clutch mechanism interposed between each of said pinions and the spindle whereon it is mounted, said mechanism permitting the pinions to turn idly on their respective spindles during the rearward or flushing movement of the said device, means for holding the gripping members in engagement with opposite sides of the material during the flushing movement of the said device, means carried by the frame for engaging the conveyor portion projecting rearwardly of the spout at the end of the flushing movement of the said device, said clutch mechanism being operative at substantially the end of the rearward movement of said device to effect a driving connection between each of the pinions and its spindle thereby to move the gripping members out of engagement with the opposite sides of the conveyor tube and to enable the rollers to move along and to press together the upper edges of the said tube during the return movement of the said

device, and means operative near the end of the said return movement for releasing the engaging means carried by the frame.

16. The combination recited in claim 15, wherein the gripping members are yieldably supported by their respective spindles.

17. Mechanism for the sanitary handling and disposition of malodorous refuse comprising, in combination, means of positioning successive portions of a refuse wrapper and conveyor comprising a strip of moisture resistant wrapping and conveying material, thereby to shape the same into the form of successive open-top refuse-receiving pockets, means operative along the top edges of the pockets for closing the same, and means for moving the said conveyor through the pocket forming means and then through the closing means thereby to form the refuse-receiving portions of the conveyor into a continuous tube.

18. Mechanism for the sanitary handling and disposition of malodorous refuse comprising, in combination, means for positioning a conveyor and wrapper comprising a strip of moisture resistant wrapping and conveying material, thereby to shape the same into successive refuse receiving pockets, closing means for successive pockets formed in said conveyor and adapted to operate along the edges thereof, a receptacle beyond the closing means to receive said refuse filled pockets and provided with a port having gates yieldably closing the same, and means for moving the said conveyor through the pocket forming means and then through the closing means and thence through the said gates.

19. In the combination recited in claim 17, the refuse receiving side of the wrapping and conveying material being entirely coated with adhesive material capable of causing opposite sides of a tubular pocket formed of such material to adhere under pressure applied to said sides, said adhesive coating being incapable of adhering to surfaces not similarly coated.

20. Mechanism for the sanitary handling and disposition of fecal matter comprising, in combination, a main cabinet having a hinged closure lid, an auxiliary cabinet attached to the main cabinet and also having a closure lid, a toilet seat hinged to the main cabinet beneath said first mentioned lid, means for supporting a supply of moisture resistant material within the cabinet and below the opening of said seat, a flushing device housed within the main cabinet at one side and below said seat and means for reciprocating said mechanism, a trough-like support beneath said seat across which said moisture resistant material is caused to intermittently travel when acted upon by said flushing device, a refuse receiving receptacle enclosed by said auxiliary cabinet, means operated by the movement of said flushing mechanism for forming the material into tubular form after having been drawn across said support, and means actuated during the flushing strokes of said flushing device to advance successive portions of the tubular-shaped material into said refuse receiving receptacle.

21. In the combination recited in claim 9, ratchet means cooperating with the said flushing device for preventing a movement of the said flushing device less than a complete stroke in either direction.

22. A dry toilet comprising in combination a seat having an opening, means for simultaneously drawing a sheet of moisture-proof material be-

neath said opening and forming the portion of the said material below said opening into an open-top pocket, means including the sheet-drawing means for forming the portions of the sheet at the rear of or beyond the seat opening into a continuous tubular form, and means for uniting the upper edges of the portions of the sheet made into such tubular form.

23. Mechanism for the sanitary handling and disposition of refuse material comprising in combination, means for supporting and positioning successive portions of an elongated strip of conveying and wrapping material in a form to constitute successive refuse receiving pockets, a reciprocable tube-forming device at the rear of the pocket-forming means, said tube-forming device including a reciprocable spout, gripping means at the front of said spout and movable therewith and adapted to engage opposite sides of the rear ends of the pockets successively and to hold such sides in engagement during the delivery movement of said spout, means for simultaneously reciprocating said spout and said gripping means, and means operative by the opposite movement of said spout for disengaging said gripping means from the opposite sides of the rear ends of said pockets.

24. Mechanism for the sanitary handling and

disposition of malodorous refuse comprising, in combination, a support, means for moving successive portions of a moisture-proof conveyor above and across said support, means for forming successive portions of the said conveyor which are 5 above the said support into open-top refuse receiving pockets, means for moving said conveyor intermittently across and beyond the said support, and means for forming into a continuous tube the successive pockets formed in the portions of the conveyor which have been moved across and beyond said support.

25. A dry toilet comprising in combination a seat having an opening, means for supporting conveying material below said opening, means 15 for shaping successive portions of the said material below the said opening into open top pockets each having rearwardly convergent sides, means for engaging the sides of the rear portions of successive pockets, thereby to pull successive portions of the said conveying material through the pocket forming means and beneath and across the seat opening, and means located at the rear of the pocket forming means for holding in tubular shape the material delivered 20 from the pocket forming means.

GEORGE OWENS HARM.
